(57) **CLAIM**

We claim the ornamental design for a Statue of Liberty novelty cap, as shown and described.

DESCRIPTION

FIG. 1 is a left side elevation view of a Statue of Liberty novelty cap that shows our design, the right side elevation view is a mirror image thereof;

FIG. 2 is a three-quarter front perspective view thereof;

FIG. 3 is a front elevation view thereof; and,

FIG. 4 is a rear elevation view thereof.
